(57) **CLAIM**

The ornamental design for a wrist band for an electronic device, as shown and described.

DESCRIPTION

FIG. 1 is a top perspective view of a wrist band for an electronic device showing our new design;

FIG. 2 is a bottom perspective view thereof;

FIG. 3 is a bottom view thereof;

FIG. 4 is a top view thereof;

FIG. 5 is a side view thereof;

FIG. 6 is an opposite side view thereof;

FIG. 7 is a front view thereof; and,

FIG. 8 is a rear view thereof.

1 Claim, 5 Drawing Sheets
